HENRY F. SCHMIDT AND DAVID W. R. MORGAN, OF SWARTHMORE, PENNSYLVANIA,
ASSIGNORS TO WESTINGHOUSE ELECTRIC AND MANUFACTURING COMPANY, A
CORPORATION OF PENNSYLVANIA.

JET CONDENSER.

Application filed December 3, 1920. Serial No. 428,062.

To all whom it may concern:

Be it known that we, HENRY F. SCHMIDT and DAVID W. R. MORGAN, citizens of the United States, and residents of Swarthmore, 5 in the county of Delaware and State of Pennsylvania, have invented a new and useful Improvement in Jet Condensers, of which the following is a specification.

Our invention relates to jet condensers 10 and similar apparatus and has for its object to provide apparatus of the character specified that shall be adapted to be employed where there is relatively little head room available, as, for example, under large turbines, the specific construction proposed 15 having the still further advantages of handling large volumes of cooling water in an efficient and compact manner and also in entraining large amounts of air with the 20 cooling water, thus permitting the use of air removing apparatus of relatively small capacities.

In the accompanying drawing, Fig. 1 is 25 a side view, partially in section and partially in elevation of a jet condenser constructed in accordance with our invention, and Fig. 2 is a view in section through the jet condenser on a plane cutting the propeller normally to its axis of rotation.

30 Heretofore, in the construction of jet condensers, it has been usual to provide a mixing chamber having at its lower end a water removal pump of the centrifugal type; this water removal pump rotates in a vertical plane.

With the use of condensers of larger capacities, the rotor diameter of the water removal pump has largely increased, and as this pump must have a certain degree 40 of submergence in order to operate satisfactorily, it has been necessary to construct the condenser of considerable overall height, an undesirable feature where the condenser is to be used in spaces of restricted head 45 room, as, for example, within turbine foundations, it being obvious that tall, slender foundation piers are not as rigid as those of the short, compact type.

In accordance with our invention, we pro- 50 vide a propeller pump at the bottom of the

mixing chamber in a jet condenser. This propeller pump rotates in a horizontal plane, thus permitting a radical reduction in the overall height in installation.

Furthermore, by proper design of the 55 propeller pump, the fluid flowing therethrough may be caused to entrain relatively large amounts of air, thus reducing the load on the air removal means.

Referring to the accompanying drawing 60 for a more detailed understanding of our invention, a jet condenser is shown provided with a nozzle chamber 5 surrounded by a water box 6 and surmounting a mixing space, as is well known and understood. 65

The mixing space 7 is provided with a throat portion 8 at the bottom thereof and a propeller pump 9 is arranged to rotate therein, this pump being provided with a flow line hub 10 of the usual design and 70 being driven by any suitable means, such, for example, as an impulse turbine 11.

The propeller chamber is provided with a conical stream line bottom 12 which directs the water delivered by the propeller 75 into an annular diffuser 13. A collecting chamber 14, preferably of volute conformation, receives the water from the diffuser 13 and discharges it into any suitable receptacle at atmospheric pressure. Partition 80 members 13' are secured radially within the diffuser 13 in order to minimize swirling or eddying motion of the condensate discharged from the propeller pump.

The operation of the structure thus described will be apparent from the foregoing. The condenser is intimately associated with a prime mover, such, for example, as a turbine, being connected directly thereto, and the exhaust steam enters the nozzle chamber 90 5 where it is brought into intimate contact with water issuing from the water box 6. The condensate rains down through the space 7 and collects at the bottom thereof, being rapidly removed by the propeller 9 and ejected through the conduit 14. The 95 degree of submergence of the propeller 9 is not so great but what considerable agitation of the water thereover takes place, thus entraining considerable amounts of air 100

- and other non-condensable gases and discharging them to the hotwell. Air removing apparatus 15 of any suitable type may be provided, if desired.
- 5 We desire to direct particular attention to the accessibility of the moving parts of our condenser. Thus the turbine or other pump driving means may be disconnected by loosening the fastening bolts 16 and by 10 slightly dropping the structure carried thereby, or the entire moving system, embodying the propeller driving means and the propeller, may be removed as a unit for inspection, repair and replacement.
- 15 While we have shown our invention in but one form, it will be obvious to those skilled in the art that it is not so limited, but is susceptible of various other changes and modifications, without departing from 20 the spirit thereof, and we desire, therefore, that only such limitations shall be placed thereupon as are imposed by the prior art or as are specifically set forth in the appended claims.
- 25 What we claim is:
1. A combined jet condenser and condensate extraction pump therefor comprising a mixing chamber, means providing a discharge throat at the bottom thereof, a propeller member rotatable in said throat, and means for discharging the condensate delivered by said propeller member.
  2. A combined jet condenser and condensate extraction pump therefor comprising a 35 mixing chamber, a propeller rotatable in the lower portion of the mixing chamber in a substantially horizontal plane, and means for discharging the condensate delivered by said propeller member.
  3. A combined jet condenser and condensate extraction pump therefor comprising a mixing chamber, a propeller rotatable in the lower portion of the mixing chamber in a substantially horizontal plane, means for 45 discharging the condensate delivered by said propeller member, said propeller being bodily removable from the condenser.
  4. A combined jet condenser and condensate extraction pump therefor comprising a 50 mixing chamber, a propeller rotatable in the lower portion of the mixing chamber in a substantially horizontal plane, means for discharging the condensate delivered by said propeller member, driving means for said 55 propeller, said propeller with its associated

driving means being removable from the condenser as a unit.

5. In a combined jet condenser and condensate extraction pump therefor, the combination with a mixing chamber, of means providing a discharge throat at the bottom thereof, and a condensate pump embodying a propeller member rotatable in said throat and driving means for said pump member.

6. In a combined jet condenser and condensate extraction pump therefor, means providing a mixing chamber, means providing a vertically opening condensate discharging throat at the bottom thereof, and a condensate pump embodying a propeller member arranged to rotate in a substantially horizontal plane within said throat.

7. In a combined jet condenser, and condensate extraction pump therefor, the combination with a mixing chamber, of means providing a discharge throat at the bottom thereof, a condensate pump embodying a propeller member rotatable in said throat and driving means for said pump member, and a plurality of radially-extending discharge members beneath said propeller member.

8. In a combined jet condenser and condensate extraction pump therefor, means providing a mixing chamber, means providing a vertically opening condensate discharging throat at the bottom thereof, and a condensate pump embodying a propeller member arranged to rotate in a substantially horizontal plane within said throat, and discharge means disposed beneath said propeller member and arranged to prevent swirling and eddying motion in the discharged condensate.

9. In a combined jet condenser and condensate extraction pump therefor, the combination with a mixing chamber, of a downwardly opening discharge throat at the bottom thereof, a propeller member arranged to rotate in said throat in a substantially horizontal plane, a stream line hub member projecting above said member, and driving means for said propeller.

In testimony whereof, we have hereunto set our names this 30th day of November 1920.

D. W. R. MORGAN.
HENRY F. SCHMIDT.
